(57) **CLAIM**

The ornamental design for portable electric pruning shears as shown and described.

DESCRIPTION

FIG. 1 is a front, left and top perspective view of portable electric pruning shears showing our new design;

FIG. 2 is a rear, right and top perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof; and,

FIG. 9 is a front, left and top perspective view of the portable electric pruning shears in accordance with our new design illustrating a battery attached to the portable electric pruning shears.

The broken lines showing of the battery in FIG. 9 illustrates the environment of the claimed design and forms no part of the claimed design. The remaining broken lines in the drawings illustrate portions of the portable electric pruning shears and form no part of the claimed design.

1 Claim, 9 Drawing Sheets
